BY **ATTORNEY**

UNITED STATES PATENT OFFICE.

JOHN FRANCIS SHEA, OF PHILADELPHIA, PENNSYLVANIA.

VACUUM-CLEANER.

985,945.

Specification of Letters Patent.

Patented Mar. 7, 1911.

Application filed December 23, 1909. Serial No. 534,747.

To all whom it may concern:

Be it known that I, JOHN FRANCIS SHEA, a citizen of the United States, and a resident of Philadelphia, in the county of Philadelphia and State of Pennsylvania, have invented certain new and useful Improvements in Vacuum-Cleaners, of which the following is a specification, reference being had to the accompanying drawings.

10 This invention particularly relates to street cleaning devices of the class wherein the surface dirt is automatically conveyed to a suitable receptacle.

The principal objects of this invention are 15 to provide a suitable vehicle with means to agitate the surface dirt and to convey said dirt, by means of a partial vacuum, into a receptacle carried thereby, and to provide means to laterally shift said agitating means 20 and conveyer with respect to the line of travel of said vehicle.

The form of this invention hereinafter described provides a car, with a beam mounted to reciprocate in a direction transverse to 25 the direction of travel of said car; a rotary brush having its shaft mounted in parallel relation to said beam in trunnions carried thereby; a countershaft carried by said beam and connected to rotate said brush; a pulley 30 slidably mounted on said countershaft and provided with a key fitted to slide in a key way extending along said shaft; means to maintain said pulley in fixed relation with respect to said car; a motor in stationary 35 relation with said car connected to rotate said pulley; a suction funnel carried by said beam; a receptacle carried by said car; a vacuum conveyer connecting said funnel and said receptacle; means in said conveyer ar- 40 ranged to create a vacuum therein; a pivotal connection and a telescopic region in said conveyer arranged to permit the funnel end of said conveyer to be shifted laterally with respect to said car.

45 This invention includes the various novel features of construction and arrangement hereinafter more definitely set forth.

In the accompanying drawing Figure 1 is 50 a central vertical longitudinal sectional view of a car embodying a convenient form of this invention, certain of the parts being

shown in elevation for convenience of illustration. Fig. 2 is a plan view of said car showing the normal position of the vacuum mechanism. Fig. 3 is a front elevational view of the car shown in Figs. 1 and 2. Fig. 4 is a transverse vertical sectional view taken on the line 4—4 in Fig. 1. Fig. 5 is a fragmentary plan view of the cleaning mechanism *per se* shifted toward the left 60 with respect to the car which is indicated in dash lines, the opposite lateral movement being indicated by dot and dash lines. Fig. 6 is an enlarged plan sectional view of a fragment of the conveyer or conduit showing the 65 pivotal connection and the telescopic region therein. Fig. 7 is an enlarged sectional view taken on the line 7, in Fig. 5.

In said figures the car comprises the receptacle 10, mounted to be carried by trucks 70 11, whose wheels 12, are arranged to traverse the track rails 13, of a street railway. Said receptacle is divided into separate compartments 15 and 16, by the horizontal filtering screen mesh 17, 18 and 19. The compartment 15, is arranged to receive the refuse 20, collected by the vacuum cleaning mechanism to be hereinafter described, and is provided with the doors 21 for the convenient removal of said refuse, and the compartment 16, provides a passage for the escape of filtered air from the compartment 15.

The car is provided with a movable frame 85 or beam 25, extending transversely with respect to the direction of movement of said car, and mounted for lateral reciprocation in suitable guides 27, provided therefor. Said beam 25, carries the suction funnels 28, which are secured thereto by the straps 29, 90 and are connected by the pipe branches 30, with the conveyer or conduit 31, which comprises the pivotal connection 32, in its vertical extension, and the telescopic region, 34, pivotal connection 35, and rotary fan 36, 95 in its horizontal portion, which is connected with the compartment 15, in the receptacle 10, by the branch pipe 38. The conveyer conduit 31, extends to the rear of the car and as shown in dot and dash lines may be 100 connected by a flexible tube 39, with the conveyer of a trailer car, not shown; the rear-

wardly extending portion of said conduit 31, being conveniently controlled by the valve 40. The fan 36, is connected to be driven through suitable connection, by the motor 41. The beam 25, is provided with the rack 42, whereby it may be laterally shifted by rotation of the hand wheel 43, disposed convenient to the operator and provided with a shaft 44, having the gear 45, in toothed engagement with said rack. In order to insure the synchronous movement of the conduit 31, with the suction funnels 28, threaded shafts 46 and 47, are journaled in bearings disposed near the hood 48, of said 10 car, and are respectively provided with miter gears 50 and 51. The gear 50, is in mesh with miter gears 52 on the shaft 53, which is provided with a gear 55, in mesh with the gear 56, on the shaft 44, and said 15 miter gear 50 is also in mesh with the miter gear 58, whose shaft is provided with the miter gear 59, in mesh with the miter gear 51. The threaded shafts 46 and 47, are in threaded engagement with the cross-heads 20 60 and 61, which respectively extend through the slot 62, in the front vestibule and through the slot 63, in said hood 48, said cross-heads are arranged to slide in guides 64 and 65 respectively and embrace 25 the conveyer conduit 31, as best shown in Fig. 1.

As best shown in Fig. 6, the conveyer conduit 31, is provided with the cylindrical pivotal connection which comprises the stationary portion of said conduit 31, having the semicylindrical end 68, fitted over the semicylindrical end 69, of the oscillatory portion, and said oscillatory portion has its end telescopically fitted over the reduced 30 end 70, of the laterally movable portion. The oscillatory portion is conveniently supported by the shoe 72, mounted to slide in the guide plate 73.

The beam 25, carries the stationary 35 brushes 75, which are oppositely inclined as best shown in Fig. 5, and tend to throw the surface refuse of the street, especially that which is adjacent to the curb, toward the center. The rotary brush 78, has its shaft 40 79, journaled in bearings in the free ends of the links 80, which are pivoted to said beam 25, and carried therewith. The brush shaft 79, is provided with pulleys connected by belts 82, with pulleys on the countershaft 55 83, which is journaled in suitable bearings 84, on said beam 25. The countershaft 83, is provided with the driving pulley 85, which has the key 86, engaged with the keyway 88, extending throughout its length, 60 and said pulley 85, is prevented from moving laterally with said shaft by the bearing brackets 87, depending from the motor casing 90. The pulley 85, is connected by the driving belt 91, with the electric motor 92, 65 which is inclosed within the motor casing

90, and may be electrically connected with the trolley wire 95, through the trolley and its supporting pole 96.

It may be observed that the surface refuse of the street is loosened by the action of the 70 brushes and that when thus agitated is drawn into the mouth of the suction funnels by the inrush of air caused by the partial vacuum created by blades 37 of the rotary blower fan 36. Furthermore it may be 75 noted that by the lateral adjustment of the mechanism above described, the entire width of the street surface may be cleaned while the vehicle traverses the center thereof.

It is not desired to limit this invention 80 to the precise details of construction and arrangement herein set forth as it is obvious that various modifications may be made therein without departing from the essential features of the invention as defined in the 85 appended claims.

Having thus described my invention, I claim:

1. In a vacuum cleaner, the combination 90 with a vehicle comprising a receptacle; of a vacuum suction funnel; a beam supporting said funnel mounted for lateral adjustment relative to said vehicle in a plane transverse to the direction of travel of said vehicle; a conveyer conduit comprising a stationary 95 portion connected with said receptacle, and a movable portion connected with the funnel, and having their adjacent ends pivotally connected to permit the lateral oscillation of said movable portion.

2. In a vacuum cleaner the combination 100 with a vehicle comprising a receptacle; of a vacuum suction funnel; a beam supporting said funnel, mounted for lateral reciprocation and having a rack; a gear arranged to engage said rack to shift said beam; a conveyer conduit comprising a stationary portion connected with said receptacle and a movable portion connected with said funnel, said portions having adjacent semicircular 105 ends interlocked to form an air tight pivotal connection, and said movable portion having a telescopic region to permit its elongation.

3. In a vacuum cleaner, the combination 115 with a car, of a beam movable transversely thereto, a suction funnel carried by said beam; a receptacle; a vacuum conduit, comprising a stationary portion and a movable portion pivotally connected therewith, connecting said funnel with said receptacle; means to reciprocate said beam, and means connected therewith arranged to reciprocate said conduit in accordance therewith.

4. In a vacuum cleaner, the combination 125 with a car, of a receptacle, a beam movable transverse to the movement of said car; a conduit having a pivotal connection; and a telescopic portion; a suction funnel, carried by said beam and connected with said recep- 130

tacle by said conduit; and means to engage said beam and said conduit to shift them laterally.

5. In a vacuum cleaner, the combination with a car, of a receptacle; a suction funnel, a conduit having a stationary portion and a movable portion connecting said funnel with said receptacle; means to shift said funnel

laterally; a cross-head slidable in suitable guide-ways and connected with said conduit, 10 to shift it in accordance with the movement of said funnel.

JOHN FRANCIS SHEA.
